COMBINED MATCH AND TOOTHPICK
HOLDER

Louis Fried, Brooklyn, N. Y.

Application March 29, 1940, Serial No. 326,702

1 Claim. (Cl. 206—29)

The present invention relates to a combined match and toothpick holder and more particularly to a stapled paper packet containing a supply of matches and a supply of toothpicks, the wrapper for the packet being similar in its construction to the well known and widely used type of folding wrapper for packaging matches alone.

The principal object of the invention is to provide a paper packet of this character which will enable one to readily carry a supply of matches and toothpicks, the two articles being maintained separate from each other in such a manner that contamination of the toothpicks by the phosphorous or other active potential igniting ingredient of the matches is prevented.

Another object of the invention is to provide a packet of this character in which provision is made for dispensing the toothpicks or at least for enabling them to be projected with ease and facility partially from the packet or holder to a position wherein they are readily accessible. In carrying out this object the invention contemplates the provision of a packet of the type set forth above which is provided with a cover having a pocket or recess therein in which the toothpicks are adapted to be housed, the pocket being formed with a display opening therein through which the toothpicks are visible and which at the same time serves as an access opening through which the toothpicks may be manually engaged and projected from the packet.

A still further object of the invention is to provide a match and toothpick holder having a cover provided with a pocket for the retention of toothpicks, the cover being formed from a single blank of material, thus resulting in economy of manufacture.

Yet another object of the invention is to provide a holder of this character containing both matches and toothpicks and possessing toothpick dispensing features and in which the presence of matches in the packet in no way interferes with the proper dispensing or manipulation of the toothpicks.

In a modified form of the invention, it is another object to provide a holder for matches and toothpicks in which the toothpicks are entirely concealed and protected from exposure, even when the packet is opened, and which is provided with an access opening having a closure flap adapted by a simple operation of the thumb to be moved to an open or extended position wherein the toothpicks are accessible to the thumb for manipulation and projection from the packet for subsequent selection and use.

The provision of a packet of this character which, although designed to enclose and package both matches and toothpicks, is substantially as compact as the usual packet containing matches alone; one which is attractive in its appearance; one which is constructed of ordinary packet-forming materials and which consequently is inexpensive to manufacture; one which is rugged and durable; and one which is well adapted to perform its required services, are further desiderata that have been borne in mind in the production and development of the present invention.

In the accompanying drawing forming a part 15 of this specification:

Figure 1 is a perspective view of a combined match and toothpick holder showing the same in open position.

Figure 2 is a front elevational view of the holder showing the same in open position.

Figure 3 is a side elevational view of the open holder.

Figure 4 is a plan view of a blank from which the cover of the improved holder is formed.

Figure 5 is a perspective view similar to Figure 1 showing a modified form of the holder.

Figure 6 is a side elevational view of the holder shown in Figure 5, and

Figure 7 is a sectional view taken substantially along the line 7—7 of Figure 6.

In all of the above described views, like characters are employed to designate like parts throughout.

Referring now to Figures 1 to 4 inclusive 35 wherein the preferred embodiment of the invention is shown, the holder or packet involves in its general organization a cover which is formed from a single strip of material, as for example paper, cardboard, or sheet metal, and includes a back portion 10, a generally rounded top portion 12, a cover flap 14, a narrow bottom portion 16, and a front retaining portion or wall 18. The retaining wall 18 extends upwardly a short distance from the bottom portion 16 and is adapted 40 to receive therebehind the lower edge of the cover flap 14 in overlapping relationship, the frictional pressure existing between the overlapping parts being sufficient to retain the holder or packet in its closed condition. In accordance with the usual practice in connection with match holders or packets of this type, a coating 20 of an abrasive, usually consisting of a mixture of red phosphorous, ground glass and gum, is applied to the wall 18 for the purpose of providing a striking 45 surface for matches contained in the holder. A

staple or other fastening device 22 extends through the back portion 10 and front wall 18 and serves to retain therebetween a match assembly or unit 24 of conventional construction.

The match assembly or unit 24 is preferably in the form of a cardboard blank from which the individual matches 26 are struck, a series of perforations (not shown) being provided in the blank to facilitate tearing off of the individual matches when they are desired for use. The match assembly 24 as shown is purely illustrative and conventional and no claim is made herein to any novelty associated therewith, the novelty of this application residing rather in the toothpick retaining features which will now be more fully described.

Referring now to Figures 3 and 4, the cover flap 14 of the packet cover member is formed of two layers or sections of the blank material including an outer section 30 and an inner section 32, the sections being folded upon each other and glued, pasted or otherwise secured or bonded in face-to-face relationship along the shaded areas shown in Figure 4 to provide a recess or pocket 33 adapted to contain and frictionally hold therein a supply of individual toothpicks 34 which are arranged in parallelism longitudinally of the packet in side-by-side relationship.

The extreme inner end of the pocket 33 adjacent the rounded top portion 12 of the packet is open and the outer or forward ends of the toothpicks 34 terminate substantially flush with or slightly inside of the forward edge of the pocket and in this manner the toothpick ends are concealed and protected from contamination by the phosphorous-treated heads of the matches 26 or by the hands of the user in extracting and manipulating the matches.

An opening 36 formed in the section 32 of the cover flap 14 provides a window or access opening in the pocket 33 through which the toothpicks are visible and through which they may be engaged by the thumb of the user and slidably moved against the frictional resistance offered by the sections 30 and 32 and projected from the pocket in the manner shown in dotted lines in Figure 2 where the ends thereof are readily accessible for withdrawal of the toothpicks individually from the packet. After the required number of toothpicks have been withdrawn, the remaining toothpicks may be retracted into the pocket by a reverse movement of the thumb where they are concealed prior to closing of the cover flap 14. The opening 36 is preferably rectangular but obviously the same may be round or of any desired contour.

Referring now to Figures 5, 6 and 7, wherein a slightly modified form of packet is shown, reference characters similar to those utilized in the preceding figures have been employed to designate the conventional features of the packet and

the features of the invention which are retained in common. In this form of the invention, the opening 36 is provided with a cover or closure flap 40 which is formed integral with the inner or forward edge of the opening and which serves normally to entirely conceal the toothpicks 33 in the pocket 36.

In utilizing this form of the invention, the cover flap 40 may readily be pushed aside or opened by manipulation thereof with the thumb and subsequently the thumb may be utilized to project the toothpicks from the pocket, and to withdraw the same in the manner previously described in connection with the form of the invention shown in Figures 1 to 4 inclusive.

It is to be noted that the section 32 of the cover flap 14, in addition to providing the pocket 36 for the toothpicks 33, also serves as a spacing sheet or member by means of which the toothpicks are maintained separate and independent from the match assembly 24.

The invention is not to be limited to the exact arrangement of parts shown in the accompanying drawing or described in this specification as various changes in the details of construction may be resorted to without departing from the spirit of the invention. Only insofar as the invention has particularly been pointed out in the accompanying claim is the same to be limited.

What is claimed is:

In a book match holder of the type having a foldable cover enclosing a match assembly, said cover being formed from a single strip of cardboard material bent transversely upon itself to provide a back portion, a folded flap portion, and a front portion spaced from the back portion and of less length than the flap portion and designed to receive therebehind an edge of the folded flap portion to maintain the holder closed, said folded flap portion consisting of an outer layer of the material and an inner layer thereof, said layers being arranged in contiguous face-to-face relationship and being secured together coextensively along the opposite longitudinal edges thereof and providing a relatively deep pocket having one open edge afforded by the inner layer of the material adjacent the juncture between the back portion and the flap portion, a plurality of toothpicks disposed in said pocket and substantially concealed therein, there being a thumb opening in said inner layer substantially centrally thereof providing for visibility of only the medial regions of the toothpicks and for manipulation thereof to slide the picks and project them from said open edge, and a closure flap normally closing said thumb opening and integrally and hingedly attached to the forward edge of the opening whereby the picks may be manipulated by a forward movement of the thumb when the closure flap is but partially open.

LOUIS FRIED.
